UNITED STATES PATENT OFFICE.

HARRY BRADLEY ROWAN, OF NORTH ATTLEBORO, MASSACHUSETTS, ASSIGNOR TO
WHITING & DAVIS COMPANY, A CORPORATION OF NEW YORK.

HAND BAG.

Application filed August 16, 1923. Serial No. 657,649.

This invention relates to hand bags of the type consisting of a frame formed of two frame members ordinarily of U-shape, which are hinged together at their ends, 5 and pieces of fabric secured to the frame members and to each other beyond the ends of the frame. The object of this invention is to provide an improved construction of such a hand bag by which its appearance 10 is made more attractive. The invention is primarily directed toward an improvement in the construction of hand bags in which the body of the bag is made of a fabric composed of interlinking metal rings, 15 ordinarily designated as link mesh. It is also of utility in hand bags of various other types.

The hand bags which have recently enjoyed the greatest popularity are those 20 which are of considerably greater length than width, and the side lines of these bags are usually designed to have graceful curves. It is particularly desirable in such bags that there should be no break or interruption 25 in the lines at the point where the frame terminates, although such interruptions have been common in bags hitherto constructed. In such hand bags the frame is usually decorated on its outer surface 30 with some appropriate pattern and it is desirable that this pattern may be carried throughout the full extent of the frame and that the fabric forming the body of the bag may be secured to the frame in such a way 35 as not to conceal this pattern and also in such a way as not to restrict the area of the frame on which the pattern is to be displayed. In the better grades of hand bags the ends of the frame members are secured 40 together by means of hinge members which extend substantially the full width of the ends of the frame members. Such hinges as these are usually made of a pair of knuckles, one on the end of each frame member, and a pintle which passes through 45 the knuckles. It is desirable that the fabric body of the bag should be secured to the frame so as to conceal these hinges so that there is no break in the line at the edge of 50 the bag due to the projection of the hinge member beyond the edge of the fabric body.

The present invention relates to an improved construction of the members of the

frame for such bags, whereby the outer edges of the fabric are in alignment with the outer edges of the frame so that there is produced what is commonly known as a stream-line effect. In the bag constructed in accordance with the present invention the fabric is secured to the inner edge of 55 the frame in the usual manner but at the ends the means of attachment of the fabric to the frame is so designed as to support the fabric to the extreme outer edges of the ends of the frame members thus concealing 60 the hinges which lie at the ends of these members. The result is that when the bag is suspended by the handle in the usual way the fabric is supported throughout its extreme width and consequently does not sag 65 or pull away from the frame. The lines of the bag are consequently unbroken and the fabric lies smooth and flat without wrinkling or bunching together. Also the means of attachment are so arranged that 70 the frame may be of uniform width throughout its length.

This desirable result is obtained by the use of frame members ordinarily of U-shape, hinged together at their ends, to 75 which pieces of the fabric are to be secured, these pieces being in turn joined together below the ends of the frame. The ends of the frame members are secured together by 80 hinges which extend practically across the ends of these members and adjacent the 85 hinges the frame members are provided with extending portions which project beyond the ends of the frame and which extend completely across these ends so as to 90 overlie and conceal the hinge members. The fabric is then secured to the frame members in any convenient manner and is also secured to the extensions so that the 95 hinges are concealed and lie within the lateral margins of the pieces of fabric, and these pieces align with the outer edges of the frame so that the contour of the bag is unbroken at this particular point. In constructing a bag in accordance with this invention it is preferable to space the extensions a short distance from the hinge members and the channel so formed makes it 100 more convenient to attach the fabric to the frame and to the extensions.

The construction above briefly described

will be better understood by reference to the accompanying drawing. In this drawing,

Fig. 1 is an elevation of a bag constructed in accordance with the invention, only the outlines of the fabric being illustrated,

Fig. 2 is an end view of the frame of the bag with the frame members closed,

Fig. 3 is a view in elevation showing the inner face of one frame member,

Fig. 4 is a detailed view similar to Fig. 3, showing but one end of one frame member,

Fig. 5 is an end view of the detail illustrated in Fig. 4,

Fig. 6 is a cross-sectional view of this detail on the line 6—6 of Fig. 4, and

Fig. 7 is another cross-section on the line 7—7 of Fig. 4,

Fig. 8 is a view in elevation of one frame member showing the decorations thereon,

Fig. 9 is an end view of a detail of the frame member shown in Fig. 8,

Fig. 10 is a cross-sectional view on the line 10—10 of Fig. 8.

Referring to this drawing, the bag is seen to consist of a frame 11, formed of two U-shaped members 12 and 13. These members are provided with locking members designated generally as 14 and 15, to one of which is attached a strap or loop 16. Each frame member has a smooth inner surface 17 and a suitably decorated outer surface 18, the latter extending unrestricted from one end of the frame member to the other.

From the inner edge of each frame member projects a thin rib 19 which extends from one end of the frame member to the other and terminates flush with the end of the frame member. The rib 19 is provided with a plurality of eyes 20 to which the fabric may be secured in any desired manner. The body of the bag here illustrated is shown as being made of link mesh fabric, the general construction of which is illustrated at 21, and in order to secure this mesh to the frame along the rib there is used a fine spiral wire 22 which is interlaced through the eyes in the rib and through the marginal rings 23 along the mesh. These pieces of mesh are joined together below the ends of the frames so that the body of the bag is, in effect, formed of a continuous piece of mesh.

Each end of each of the frame members is provided with a hinge knuckle 23 which extends approximately half way across the end of the main body of the frame member and which is located so that a portion of the knuckle indicated at 24 lies beyond the face

25 of the frame member. These knuckles are drilled as at 26 for the insertion of a hinge pin and as is indicated in Fig. 6 at 27, the end of the frame members are channelled to form a recess into which the co-operating hinge knuckle on the other frame

member may enter when the two knuckles are connected together by the pin. The arrangement of the parts is such that when the two frame members are placed back to back the knuckles lie side by side with their apertures in registry, as is shown in Fig. 2.

Projecting from the front surface of each frame member at the ends thereof, is an extension 28 spaced from that portion of the frame which over-lies the co-operating knuckle to form the channel 29. The extension 28 has a plurality of holes 30 drilled therethrough and these holes are carried as near the outer edge of the frame as may be.

It will be noted on reference to Fig. 1

that the mesh which forms the body of the bag is not interrupted near the end of the frame members, but the outer lines of the body of mesh continue from the extreme edges of the frame members. This unbroken, or stream-line, effect is brought about by the manner in which the mesh is attached to the frame members at their ends. As has previously been explained, the two pieces of mesh are attached along the sides of the frame members by any convenient means, preferably by the spiral wire 22 interlacing with the holes 20 of the rib 19, and with the marginal links of the pieces of mesh. It is possible to continue this spiral wire beyond the ends of the rib 19, bend it around the corners of the ends of the frame members and then interlace it with the apertures 30 in the extension 28 and with the links so that parts of the pieces of mesh will lie below these extensions. Preferably, however, the connection of the mesh to the frame at the ends of the frame members will be brought about by the use of separate links 31 which are inserted through the marginal links of the mesh at this point and then through the apertures 30. These links serve the same purpose as the spiral wire but make a somewhat stronger union which is desirable at this point where the action of opening and closing the frame is likely to cause wear on the connecting members. The spacing of the extensions 28 from the knuckles and the portions of the ends of the frame members which over-lie the knuckles

as at 27 provides a channel 29 which permits of the ready insertion of the links 31 through the holes 30. The pieces of mesh to be mounted on the frame are previously cut to the desired shape and the attachment of these pieces to the frame members is easily carried on even at the ends of the frame where the mesh is to over-lie the hinges.

It will be seen that in the hand bag constructed in accordance with the present invention, the fabric or mesh is easily attached to the frame members so as to produce the desired stream-line effect at the ends of these members and, at the same time,

the fabric is supported across the ends of the frame members so as to prevent sagging or pulling away of the fabric. By on-setting the hinge knuckles at the ends of the frame members as is shown in Fig. 3, where the knuckles are both placed at the right hand edge of the frame member, it will be seen that when a pair of such members are placed back to back the co-operating knuckles take the desired positions. Also the desired stream-line effect with the hinge concealed is brought about in the present hand bag without any diminution in the area of the outer surface of the frame members throughout their length. In this way a decorative pattern may be employed on the face of the frame members and this pattern may be repeated without interruption from one end to the other of each member.

20 While the frame members have been illustrated and described as being provided with an extending rib or fin 19 having a series of apertures through which the spiral wire is interlaced for the purpose of attaching the fabric to the frame members. It is also possible to employ frame members in which this fin is dispensed with, the spiral wire being interlaced with the marginal links of the pieces of mesh and then being soldered directly to the inner faces of the frame members. Such a construction is illustrated in Figs. 8, 9 and 10, in which there is shown a frame member with the extensions 28 at the ends and to the inner faces of which is soldered a spiral wire 22 such as has previously been described. This wire is soldered at a point between the edges of the inner face so as to be protected to some extent when the bag is in use.

40 I claim:

1. A hand bag having a frame consisting of two frame members pivotally connected at their ends, integral plate-like extensions from the ends of the frame members over-lying and partially concealing these connections and pieces of mesh secured to the frame and to the extensions and secured together beyond the ends of the frame.

2. A hand bag having a frame consisting of two frame members hinged together at their ends, the hinges extending substantially across the ends of the frame members, integral plate-like extensions from the ends of the frame members over-lying and partially concealing the hinges and spaced therefrom and pieces of mesh secured to the frame and to the extensions and secured together beyond the ends of the frame.

3. A hand bag having a frame consisting of two frame members, a hinge knuckle mounted at the back edge of each end of each frame member, an extension projecting from the front edge of each end of each frame member to over-lie the said knuckle

and pieces of mesh secured to the frame and 65 to the extensions and secured together beyond the ends of the frame.

4. A hand bag having a frame consisting of two members, integral hinge knuckles extending from the rear faces of each frame member at the edges thereof, these hinge knuckles having a length equal to approximately one half of the width of the frame members, integral extensions projecting from the ends of the frame members at the 70 front surfaces thereof and extending entirely across the ends of the frame members, these extensions lying in spaced relation from the hinge knuckles, and pieces of mesh secured to the frame members and to the extensions to over-lie and conceal the knuckles and secured together beyond the ends of the frame.

5. A hand bag having a frame comprising two members, a hinge knuckle mounted on 85 each end of each member intermediate the edges thereof, these hinge knuckles receiving a pintle and forming a hinge extending substantially across the ends of the members, a plate-like extension projecting from 90 the end of each member in spaced relation to the knuckle to overlie and partially conceal the same, and pieces of mesh secured to the frame and to the extensions and secured together beyond the ends of the frame. 95

6. A hand bag having a frame consisting of two frame members connected at their ends by hinges extending substantially across the ends of the frame members, integral plate-like extensions from the ends of 100 the frame members over-lying the hinges and spaced therefrom, an apertured rib projecting from the inner edge of each frame member and terminating adjacent the inner ends of the extension, and pieces of mesh 105 secured to the frame members by means of a continuous spiral wire interengaging with the marginal links of the mesh and with the apertures in the rib and attached to the extensions by means of rings, these pieces 110 of mesh being secured together beyond the ends of the frame.

7. A hand bag comprising a pair of substantially U-shaped frame members provided with hinge knuckles at their extremities adapted to co-operate to connect the frame members together, a plate-like extension projecting from each end of each of the frame members in spaced relation to the knuckle and adapted to over-lie and partially conceal the same, and pieces of mesh secured to the frame members by means of a spiral wire and secured also to the extensions, these pieces of mesh being united beyond the ends of the frame members. 115 120 125

In testimony whereof I affix my signature.

HARRY BRADLEY ROWAN.
